COMBINED BOTTLE AND CAP THEREFOR

Keizo Saji, Kawanishi, Japan, assignor to Suntory
Kabushiki Kaisha, Osaka, Japan

Filed Jan. 27, 1969, Ser. No. 15,518

Claims priority, application Japan Sept. 24, 1968

Term of patent 14 years

Int. Cl. D9—01

U.S. Cl. D9—33

FIG. 1

FIG. 3

FIG. 5

FIG. 2

FIG. 4

FIG. 6

FIG. 1 is an elevational view of a bottle showing my new design, the opposite side being the same in appearance as the side shown;

FIG. 2 is an elevational view looking from the right of FIG. 1, the opposite side being the same in appearance as the side shown; and

FIG. 3 is a top plan view thereof.

The stippling indicates contrasting surface texture.

I claim:

The ornamental design for a combined bottle and cap therefor, substantially as shown and described.
